UNITED STATES PATENT OFFICE.

EDWIN D. TILLSON, OF EVANSTON, ILLINOIS.

LIGHTING DEVICE.

1,373,845.

Specification of Letters Patent.

Patented Apr. 5, 1921.

Application filed July 8, 1918. Serial No. 243,982.

To all whom it may concern:

Be it known that I, EDWIN D. TILLSON, a subject of the King of Great Britain, residing at Evanston, Cook county, Illinois, have 5 invented a new and useful Improvement in Lighting Devices, of which the following is a specification.

My invention relates primarily to that type of lighting device in which comparatively high power electric lamps are employed. While the invention is applicable to domestic use, it is primarily fitted for commercial uses as in offices, drafting rooms, stores, factories, etc., where comparatively 15 brilliant general lighting is required and yet where it is desirable, if not imperative, to protect the eyes of the persons beneath and within close range. My invention is especially desirable in connection with the 20 so called "nitrogen lamps" which are ordinarily extremely bright and in which the filament occupies but a small compass—usually considered as constituting a point source.

25 The general object of the invention is to produce a lighting fixture or device appropriate for the conditions above mentioned, and to facilitate an understanding of the invention reference is made to the accompanying drawing which is a side elevation chiefly in axial section showing the complete apparatus. In carrying out my object, I have employed a comparatively flat reflector above the light source which, in the 30 completest form, is combined with a plurality of coaxial bands or rings of translucent substance. These bands are arranged at different levels and placed in such manner as to cut off, from the eye of the observer, all di-

35 rect rays emanating from the filament. The translucent bands impart the cheerful appearance desired in such places as the ones mentioned and yet they shield the eye from the direct rays. My device also has the advantage of not showing an image of the 40 source to any one directly under or near the device. It will be understood that, with a so called "point source" of light, especially when of great brilliance, a reflector is apt 45 to show the image in such a way as to be ungrateful to the eye; and my device is so constructed that such image will not be seen except by persons standing at such a distance, laterally, that no disagreeable effect 50 will be experienced.

It is, of course, known that in commercial

buildings, especially factories, there is apt to be a considerable amount of dust. When ordinary bowls are employed beneath the light source for the purpose of eye protection, this dust accumulates all too rapidly and, unless the bowls are frequently cleaned, the light is dimmed and the bowl presents an unpleasant appearance. It is one of my objects to provide a plurality of annular bands 60 or rings which will possess the advantages of a bowl and yet have sheer sides to which the dust will practically be unable to adhere. Another object of the invention is to make the translucent bands separately removable 65 so that if only one needs cleaning, the other need not be disturbed.

I obtain my objects by the construction illustrated in the accompanying drawing in which the light source is in the form of an 70 electric bulb 1, preferably of the gas filled or nitrogen filled type. This has a filament 2 which forms the source proper and usually occupies a small space so that the light practically emanates from a point. The lamp 75 screws into a socket 3 which is supported by any appropriate type of fixture 4. A reflector 5 is also supported from said fixture by any suitable means which form no essential part of my present invention and need 80 not be described in detail.

The reflector has a central opening 6 of somewhat larger diameter than the neck of the bulb, thus affording ventilation. While the exact form is immaterial, the reflector is, 85 in general, comparatively flat and near enough to the level of the filament to insure that a considerable portion of the rays reflected from it will be distributed at wide angles.

Below the reflector, preferably about on a level with the filament, is an annular band or ring 8 of translucent material arranged concentric with the vertical line passing through the filament and so placed and dimensioned that its upper edge will intercept the rays which would otherwise escape below edge 5^a of the reflector 5. This translucent element 8 is, in the present case, supported upon the hooks 10 formed at the 105 outer ends of rods 11 which hang from hooks 12 secured to the reflector.

Coaxial with the element 8 is a second translucent annular band 14 which, in the present case, is entirely below the filament 110 and is secured to a ring 15 by means of set screws 16 or other suitable devices. Ring

15 is supported by the rods 11, although any appropriate type of suspending means may be employed. This second translucent element is of considerably smaller diameter 5 than the first translucent element 8 and its upper edge is so located as to intercept the rays which would escape beneath the lower edge of the element 8. Furthermore the surfaces of both the elements 8 and 14 are sheer 10 enough to prevent the lodging of any considerable amount of dust. By preference, the upper element converges toward the top while the lower one converges toward the bottom. This enables the translucent elements to cover a greater spherical area centered at the filament. 15

While not essential, it is desirable to provide a reflector 17 directly beneath the bulb, its diameter being sufficient to intercept the 20 rays which would otherwise escape past the lower edge of the translucent element 14. This reflector is suspended by arms 18 supported by the ring 15.

In practice, the only light rays which will 25 reach the reflector direct are those which will be thrown outward at a wide angle as illustrated by the ray B-B. Persons observing these rays will be so far away horizontally that the eyes will not be bothered 30 by direct reflection. All of the other rays, except those between the lines A-A will be diffused and softened before reaching the eye of those within the illuminated area. In the present case, a small spot directly 35 beneath the device will be shaded from direct rays, although on account of the flaring shape of the upper translucent element 8, even this spot will receive illumination in proper degree.

40 From the foregoing it would be seen that the device is capable of illuminating a wide area and presents a cheerful appearance and yet it effectually protects the eyes of all persons. Those persons far away may 45 receive a directly reflected light but they must be at a distance sufficient to prevent any unpleasant effect upon the eyes. The light which will reach persons nearer to the device will be reflected and diffused in such 50 manner as to prevent any ungrateful effect and the appearance of any direct image reflected from the reflector. Another advantage is that the two translucent elements are individually removable, and on account of 55 the outward flaring shape of the uppermost

translucent element it will seldom be necessary to take it down for cleaning purposes. The lower element 14 having slightly converging sides may need cleaning occasionally but it can be removed without disturbing the element 8 above it. Thus the device is convenient as well as efficient as a lighting device. 60

Having thus described my invention what I claim as new and desire to secure by Letters Patent, is:— 65

1. A lighting device having a light source, a reflector above said source, an upper annular translucent element, open top and bottom, surrounding said source and having its upper edge high enough to intercept the rays which would escape the edge of the reflector, a lower and smaller annular translucent element open top and bottom, surrounding said source and having its upper edge high enough to intercept the rays which would escape beneath the lower edge 75 of the upper translucent element, said lower element having a substantially sheer inner concave surface facing inward and upward, 80 and said upper element having a concave inner surface facing inward and downward.

2. A lighting device having a light source, a reflector above said source, and a plurality of annular translucent elements arranged at 85 different levels below said reflector, the upper translucent element being of smaller diameter than the reflector and the second translucent element being of smaller diameter than the first translucent element, the 90 upper edge of the upper translucent element being high enough to intercept the rays which would escape the edge of the reflector and the upper edge of the lower translucent element being high enough to intercept the rays which would escape the lower edge of the upper translucent element, and an opaque disk directly beneath the light source and having a diameter great enough to intercept the rays which would escape the lower edge of the lower translucent element, the upper translucent element having a concave inner surface facing inward and downward, and the second translucent element having a concave inner surface facing inward and upward, and the radii vectores of both the upper and the second translucent elements lying entirely within the respective elements. 100 105

EDWIN D. TILLSON.
